FRONT-END STAND FOR VEHICLES

Robert W. Lemley, 11714 Lone Shadow Trail,
San Antonio, Tex. 78233

Filed Oct. 5, 1972, Ser. No. 294,998

Term of patent 14 years

Int. Cl. D12—05

U.S. Cl. D12—55

FIG. 1 is a rear elevational view of a front-end stand for vehicles showing my new design.

FIG. 2 is a side elevational view thereof.

FIG. 3 is a front elevational view thereof.

FIG. 4 is a top plan view thereof.

I claim:

The ornamental design for a front-end stand for vehicles, as shown.
